UNITED STATES PATENT OFFICE.

HENRY GROSSMAN, OF NEW YORK, N. Y.

DESIGN FOR A CHAIR.

No. 38,875.

Specification for Design.

Patented Nov. 5, 1907.

Application filed September 6, 1907. Serial No. 391,733. Term of patent 7 years.

To all whom it may concern:

Be it known that I, HENRY GROSSMAN, a citizen of the United States, residing at New York, in the county of New York and State of New York, have invented a new, original, and ornamental Design for Chairs, of which the following is a specification, reference being had to the accompanying drawing, forming part thereof.

The figure is a perspective view of a chair, showing my new design.

I claim:

The ornamental design for a chair as shown.

HENRY GROSSMAN.
